FRAME MOLDING

Greg Copeland, 114 Beach Terrace,
Wayne, N.J. 07470

Filed Dec. 3, 1974, Ser. No. 529,187

Term of patent 14 years

Int. Cl. D6—07

U.S. Cl. D6—232

The figure is a perspective view of a frame molding showing my new design. It is understood that the far edge is broken off to indicate indeterminate length. The left outside surface is unornamented.

The characteristic feature of the design resides in the configuration of the outwardly facing surfaces.

I claim:

The ornamental design for a frame molding, as shown and described.
